US00D908210S

(12) **United States Design Patent** (10) **Patent No.:** **US D908,210 S**
(45) **Date of Patent:** **** Jan. 19, 2021**

(54) **INJECTION PEN**

(71) Applicant: **Companion Medical, Inc.**, San Diego, CA (US)
(72) Inventors: **Sean Saint**, San Diego, CA (US); **Jack Pryor**, San Diego, CA (US); **Arnold Holmquist**, San Diego, CA (US); **Cory McCluskey**, San Diego, CA (US)

(73) Assignee: **Companion Medical, Inc.**, San Diego, CA (US)

(**) Term: **15 Years**

(21) Appl. No.: **29/652,378**

(22) Filed: **Jul. 28, 2020**

Related U.S. Application Data

(62) Division of application No. 29/647,370, filed on May 11, 2018, now Pat. No. Des. 893,020.

(57) **CLAIM**

The ornamental design for an injection pen, as shown and described.

DESCRIPTION

FIG. 1 is a perspective view of the injection pen;

FIG. 2 is a side elevation view thereof;

FIG. 3 is another side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken-line disclosure shown in the drawings is understood to be for illustrative purposes only, and forms no part of the claimed design.

1 Claim, 4 Drawing Sheets
